UNITED STATES PATENT OFFICE

ROBERT H. HARDIN, OF BAKERSFIELD, CALIFORNIA

AIR-COOLING DEVICE

Application filed February 15, 1930. Serial No. 428,799.

This invention relates to a device primarily designed for the use in reducing the temperature in the rooms of public buildings, hotels, schools or the like, by supplying cold air to the rooms.

Another object of the invention is to provide a device of this character which may be effectively employed as a ventilating system for supplying pure air to the rooms of buildings.

A still further object of the invention is to provide air tubes through which the air under treatment, is forced, the air tubes being of such construction as to insure the maximum cooling of the air by the minimum amount of cold.

With the foregoing and other objects in view, which will appear as the description proceeds, the invention resides in combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a longitudinal sectional view through an air cooling device constructed in accordance with the invention.

Figure 2 is a sectional view taken on line 2-2 of Figure 1.

Figure 3 is a sectional view taken on line 3-3 of Figure 1.

Referring to the drawings in detail, the device comprises a box-like body portion indicated generally by the reference character 5, the body portion being constructed of suitable sheet metal material or red clay covered with asbestos or other suitable heat insulating material, such as indicated by the reference character 6.

The body portion 5, which is in the form of a tank, is formed with a transverse passageway extending directly through the body portion, the ends thereof communicating with the atmosphere. The bottom of the members in the passageway are closed, as clearly shown by Figure 1 of the drawings so that water contained in the body portion or

tank, may enter the hollow members and remain.

Arranged within the passageway and disposed vertically, are a plurality of wide flat hollow members 7 which are arranged in parallel spaced relation with each other defining transverse passageways, the upper edges of the members 7 being open and in communication with the interior of the body portion or tank, so that water contained in the body portion may enter the members 7, to cool them.

As shown by the drawings, the members 7 are formed with offset end portions 8 to cause the air passing between the members 7 to take an irregular course, retarding the air and insuring the air contacting with both sides of the members 7 to cool the air.

The reference character 9 designates a blower housing in which a blower not shown, is mounted, the blower being operated by the belt 10 operating over the pulley 11. This belt 10 operates over a suitable power pulley not shown. The pipe 12 establishes communication between the blower housing 9 and the spaces or passageways between the members 7, so that air from the blower housing may be directed through the passageways or spaces. After the air passes through the spaces or passageways between the members 7, it may be supplied to the rooms of buildings, in any desired manner.

Water and ice are placed in the body portion 5 so that the cold from the ice will cool the water which will be transmitted to the members 7 to cool them.

The reference character 13 designates a removable cover for the body portion so that water and ice may be readily placed within the body portion and the cover placed in position to close the body portion. A spigot such as indicated by the reference character 14 is mounted on the body portion and extends into the body portion so that ice water may be withdrawn from the body portion for drinking purposes.

I claim:

1. In a device of the character described, a body portion for the reception of water and ice, said body portion having a trans-

versely disposed passageway, a plurality of hollow members arranged within the passageway, said hollow members having offset end portions to cause air forced between the hollow members to take an irregular path, means for forcing air between the hollow members, and means for causing the water in the body portion to enter from the top to the bottom of the hollow members.

- 5 10 2. In a device of the character described, a body portion, a passageway extending through the body portion, hollow members arranged in parallel spaced relation with each other, positioned in the passageway, said 15 hollow members having angularly disposed end portions, means for forcing air between the hollow members, and means for causing water to enter through the body portion.

In testimony that I claim the foregoing 20 as my own, I have hereto affixed my signature.

ROBERT H. HARDIN.
